Primary Examiner — Keli L Hill

(57) **CLAIM**

The ornamental design for a handset, as shown and described.

DESCRIPTION

The patent or application file contains at least one drawing executed in color. Copies of this patent or patent application publication with color drawing(s) will be provided by the Office upon request and payment of the necessary fee.

1.1 is a front elevation view of the first embodiment of a handset.

1.2 is a right side elevation view.

1.3 is a left side elevation view.

1.4 is a rear elevation view.

1.5 is a top plan view.

1.6 is a bottom plan view.

1.7 is a front elevation view of the second embodiment of a handset.

1.8 is a rear elevation view.

1.9 is a right side elevation view.

1.10 is a front, right side and bottom perspective view. The screen which is shown in red shading in the reproductions 1.7 and 1.10 forms no part of the claimed design.

**1 Claim, 10 Drawing Sheets
